BRIDLE STRAP OR TAPE

Joseph H. Burroughs, New Rochelle, N. Y.

Application February 17, 1933. Serial No. 657,317

5 Claims. (Cl. 84—253)

This invention relates to bridle straps, and more particularly to improved means for securing a bridle strap to the catcher shank of a piano action.

6 This invention is primarily adapted for use where it is necessary to repair a piano action by the replacement of bridle straps, as this is one of the frequent causes of replacement due to the fact that bridle straps wear and break.

10 My invention includes an improved means whereby one end of the bridle strap may be looped about the catcher shank and be securely held thereon, and which is noiseless in use.

A further object is to provide a bridle strap and 15 coupling means therefor which facilitate the insertion of new bridge straps in piano actions and insure perfect coupling means without any sound vibrations due to the coupling means.

With these and other objects in view, the invention consists in certain novel features of construction and combinations and arrangements of parts, all of which will be more fully herein-after described and pointed out in the claims.

In the accompanying drawing,—

20 Figure 1 is a view mainly in side elevation but partly in section, illustrating my improved bridle strap in operative position on a piano action;

Figure 2 is a view mainly in elevation but showing the coupling device in section on my improved 25 bridle strap;

Figure 3 is a perspective view of the rubber sleeve which I employ as part of my improved coupling device; and

Figure 4 is a perspective view of the metal 30 sleeve which I employ as part of my improved coupling device.

1 represents a hammer shank carrying a hammer head 2 at one end and connected to the hammer butt 3 at its other end. 4 is the usual 35 catcher shank extending from the hammer head and carrying a catcher 5 which is provided with the usual opening 6. 7 represents my improved 40 bridle strap which constitutes a strip of suitable flexible material having a wedge-shaped bridle strap tip 8 secured on the face thereof at one 45 end having an opening 9 therein to receive the ordinary bridle wire 10. By making this wedge-shaped tip 8 of felt it can be readily manipulated through the coiled or twisted end of the bridle 50 strap wire and be suitably coupled thereto, and present a strong connection.

55 My invention has particularly to do with the manner of securing the bridle strap to the catcher shank, and for this purpose I employ a coupling device which consists of an outer rubber or other

resilient sleeve 10 and an inner non-resilient or metal sleeve 11. The metal sleeve 11 is designed to fit snugly within the rubber sleeve 10, and is shorter than the bore of said rubber sleeve and is preferably curved inwardly at its inner end, 60 as indicated at 12.

The outer end of the metal sleeve is provided with an annular outwardly projecting flange 13 which is preferably slightly curved in cross section, as clearly shown in Figure 2 of the drawing. In locating this coupling device on the strap I first project the end of the strap through the bore of the rubber sleeve 10 and then insert the metal sleeve 11, clamping a portion 14 of the strap between the metal sleeve 11 and the rubber 70 sleeve 10. An intermediate portion of the strap 7 is then projected through the bores of both sleeves forming a loop 15, and this loop 15 is positioned over the catcher and around the catcher shank; the other end of the strap is then projected through the opening 6 in the catcher and the tape is drawn taut to reduce the diameter of the loop 15, and securely clamp the catcher shank with the rubber sleeve 10 located against the 75 catcher 5 so as to prevent any metallic contacts, 80 thus preventing any sound due to the coupling device.

A device of this character can be easily and quickly placed in operative position when the bridle strap 7, with which the action is initially 85 provided, is broken or injured, and a strong, durable connection is thus provided.

While I have illustrated what I believe to be the preferred embodiment of my invention it is to be distinctly understood that various slight 90 changes may be made with regard to the form and arrangement of parts without departing from my invention, and hence I do not limit myself to the precise details set forth but consider myself at liberty to make such changes and alterations 95 as fairly fall within the spirit and scope of the claims.

What I claim is:

1. A bridle strap for piano actions including inner and outer sleeves, and a strip clamped between the sleeves and looped through the sleeves for engagement with the catcher shank of a piano action.

2. In combination with a bridle strap, a coupling device for securing one end of the strap, 105 said coupling device including an outer resilient sleeve and an inner non-resilient sleeve between which an end of the strap is clamped.

3. A coupling device for bridle straps comprising an outer rubber sleeve, an inner metal sleeve 110

fitting snugly within the bore of the outer sleeve, and said metal sleeve having a flanged end bearing against the end of the rubber sleeve.

4. A coupling device for bridle straps comprising an outer rubber sleeve, an inner metal sleeve fitting snugly within the bore of the outer sleeve, said metal sleeve having a flanged end bearing against the end of the rubber sleeve, and said metal sleeve having an inwardly curved inner 10 end reduced in diameter.

5. The combination with a bridle strap of a coupling device including inner and outer sleeves between which the ends of the strap are clamped and the strap looped through both sleeves, and a wedge-shaped bridle strap tip secured on the face 80 of the strap at one end for coupling engagement with a bridle wire.

JOSEPH H. BURROUGHS.
